UNITED STATES PATENT OFFICE

ROBERT HUDSON WAGER, OF JERSEY CITY, NEW JERSEY

AIR REGISTER

Application filed August 16, 1928. Serial No. 300,046.

The invention relates to air registers and more particularly to those designed for ventilating purposes, for instance in the ceilings of staterooms, hotel and office rooms, etc.

5 It is one aim of the invention to provide an improved register of simple and inexpensive construction which may be easily adjusted to admit the desired amount of air or to stop such admission, and will be effectively held 10 against accidental movement from its adjusted position.

Another object is to provide an air deflector mounted in a novel manner for preventing direct inrush of air, with consequent danger 15 of disarranging ladies' apparel and hair.

Yet another aim is to provide the air deflector with a hub of such form as to encase a spring which is instrumental in holding the register in adjusted position.

20 With the foregoing in view, the invention resides in the novel subject matter hereinafter described and claimed, description being accomplished by reference to the accompanying drawings.

25 Fig. 1 is a side elevation showing the register secured to a ceiling through which an air admission pipe extends.

Fig. 2 is a vertical sectional view through the parts shown in Fig. 1.

30 Fig. 3 is a top plan view partly in horizontal section.

Fig. 4 is a horizontal sectional view on line 4—4 of Fig. 2.

Fig. 5 is a detail vertical section on line 35 5—5 of Fig. 3, parts being omitted.

Fig. 6 is a detail vertical sectional view on the correspondingly numbered line of Fig. 3.

Fig. 7 is a side elevation of the shaft for turning the movable disk which co-acts with 40 a stationary disk in controlling the admission of air.

The drawings above briefly described illustrate the preferred form of construction and while this construction will be herein specifically explained, it is to be understood that within the scope of the invention as claimed, variations may be made.

The device embodies a stationary disk 10 having a central shaft-receiving opening 11 45 and a plurality of air-conducting openings 12

spaced around said opening. A continuous wall 13 is integral with the peripheral portion of the disk 10 and at its free edge is provided with an outstanding attaching flange 14 adapted to be secured to a ceiling 15 or 55 other support, by bolts 16 or any other desired fasteners. In the present showing, an air admission pipe 17 passes through an opening in the ceiling or other support 15 and is snugly received within the wall 13. 60

A rotatable disk 18 lies against the disk 10, within the confines the wall 13, said rotatable disk 18 being formed with a central opening 19 and with a plurality of air-conducting openings 20 spaced around said opening 19, 65 for communication when desired with the openings 12. The relation of openings 12—20 is such that upon turning of the disk 18 to one position, no passage of air can take place through said openings. Disk 18 is provided 70 with a peripheral, limit lug 21 which is operable between a pair of circumferentially spaced lugs 22 formed on the inner side of the wall 13. When lug 21 is in contact with one of the lugs 22, the register is open to the maximum and when said lug 21 contacts with the other of the lugs 22, said register is fully closed. In intermediary adjustments, the register will of course admit the desired quantity of air. 75

An operating shaft 23 is provided for the disk 18, one end of this shaft being passed through the opening 19. By means of a nut 24, the disk 18 is clamped against a shoulder 25 on the shaft 23, and relative rotation of 80 shaft and disk is prevented by an appropriate key 26. Shaft 23 passes through the opening 11 and projects outwardly beyond the disk 10, said shaft being provided near its outer end, with an outwardly facing shoulder 27. 85 A hand wheel or other handle 28 is secured upon the outer end of shaft 23 and is locked thereon by a lock-nut 29, and said handle and shoulder are instrumental in securing a substantially conical air deflector 30 to the shaft. 90

The deflector 30 is provided with a central hub 31 having a longitudinal socket 32 opening through one of its ends, and an opening 33 extending to its other end from the socket bottom 34. The outer end portion of the shaft 100

23 passes through the opening 33, the socket bottom 34 abuts the shoulder 27, and the handle 28 abuts the outer end of the hub 31, thereby tightly securing the latter to the shaft.

5 A coiled compression spring 35, surrounds the shaft 23 within the socket 32, the ends of said spring abutting the stationary disk 10 and the socket bottom 34 respectively. Thus, the spring acts longitudinally upon the shaft 23 and re-acts upon the stationary disk 10, thereby holding the rotatable disk 20 in tight frictional contact with said stationary disk 10, so that said rotatable disk is effectively held in any position to which it may be adjusted. When disk 18 is being held in one of its adjusted positions, a slight space 36, exists between the disk 10 and the hub 31. This permits sufficient inward movement of the shaft 23, incident to turning the handle 28, 10 to relieve the friction between the disks 10-18, permitting easy turning of the latter.

It will be seen from the foregoing that I have provided a rather simple and inexpensive, yet an efficient and desirable register for ventilating purposes. Any desired amount of air may be admitted or the admission of air may be entirely checked, as occasion may demand. When air is being admitted, the deflector 30 prevents the discharge of a direct blast into the room from the pipe 17 and hence there is no danger of disarranging the hair or the apparel of its occupants. The central hub 31 of this deflector 30 acts not only as part of a unique arrangement for securing the deflector to the shaft 23, but serves also as encasing means for the spring 35 and hence assists materially in providing a compact structure having an exceptionally good appearance. In case the ventilator should be hard to open or close from any cause so that it could not be readily turned by the handle 28, the periphery of the air deflector 30 may be grasped with one or both hands so that said deflector may be used as 45 turning means for the shaft 23. As said periphery of deflector 30 is a greater distance from the shaft than the periphery of the handle 28, more turning leverage may be exerted on the shaft and consequently it may be readily rotated.

The exact details disclosed have in actual practice proven to be advantageous to the maximum from numerous standpoints. These details are therefore preferably followed as above stated. However, attention is again invited to the fact that within the scope of the invention as claimed, variations may be made.

I claim:—

60 1. In a room-ventilating air register, a stationary disk having air-conducting openings, a rotatable disk disposed at one side of said stationary disk and having air-conducting openings for registration with those aforesaid, a shaft having a driving connection with

said rotatable disk, and an air deflector centrally secured to and carried solely by the room-facing end of said shaft, said deflector being exposed at the room side of the register and hence accessible for use as a handle for turning the shaft and the rotatable disk. 70

2. In an air register, a stationary disk having a central shaft-receiving opening and air-conducting openings around the same, a rotatable disk lying against one side of said stationary disk and having air-conducting openings for registration with those aforesaid, a shaft having a driving connection with said rotatable disk and passing rotatably through said shaft-receiving opening, a handle on the outer end of said shaft, and an air deflector centrally connected to and carried solely by said shaft between said handle and said disks. 75

3. In an air register, a stationary disk having a central shaft-receiving opening and air-conducting openings around the same, a rotatable disk lying against one side of said stationary disk and having air-conducting openings for registration with those aforesaid, a shaft secured to said rotatable disk and passing rotatably through said shaft-receiving opening, said shaft having an outwardly facing shoulder near its outer end, an air deflector having a central opening through which the outer end portion of said shaft passes, and an operating handle secured on the outer end of said shaft and holding said deflector against said shoulder. 85

4. In an air register, a stationary disk having a central shaft-receiving opening and air-conducting openings around the same, a rotatable disk lying against one side of said stationary disk and having air-conducting openings for registration with those aforesaid, a shaft secured to said rotatable disk and passing rotatably through said shaft-receiving opening, a deflector having a central hub secured against longitudinal movement on said shaft and extending substantially to said disks, said hub having a socket opening toward said disks and a compression spring in said socket abutting one of said disks to frictionally hold the rotatable disk against the stationary disk. 100

5. In an air register, a stationary disk having a central shaft-receiving opening and air conducting openings around the same, a rotatable disk lying against one side of said stationary disk and having air-conducting openings for registration with those aforesaid, a shaft secured to said rotatable disk and passing rotatably through said shaft-receiving opening, said shaft having an outwardly facing shoulder near its outer end, an air deflector having a central hub formed with a longitudinal socket opening through one of its ends and with an opening from the socket bottom to its other end, said hub surrounding said shaft with said socket bottom abut- 110

ting said shoulder, means co-operable with said shoulder in securing the deflector on the shaft, and a compression spring surrounding said shaft, said spring abutting one of said disks and said socket bottom to hold the rotatable disk frictionally against said stationary disk.

6. In an air register, a stationary disk having a central shaft-receiving opening and air-conducting openings around the same, a rotatable disk lying against one side of said stationary disk and having air-conducting openings for registration with those aforesaid, a shaft secured to said rotatable disk and passing rotatably through said shaft-receiving opening, said shaft having an outwardly facing shoulder near its outer end, an air deflector having a central hub formed with a longitudinal socket opening through one of its ends and with an opening from the socket bottom to its other end, said hub surrounding said shaft with said socket bottom abutting said shoulder, a handle secured on the outer end of said shaft and coacting with said shoulder in securing said deflector in place, and a compression spring surrounding said shaft, said spring abutting one of said disks and said socket bottom to hold the rotatable disk frictionally against said stationary disk.

7. A structure as specified in claim 1, together with a spring around said shaft for holding the two disks in frictional contact with each other, said air deflector having a central hub within which said spring is confined.

8. A structure as specified in claim 2; together with a spring around said shaft for holding the two disks in frictional contact with each other, said air deflector having a central hub within which said spring is confined.

9. In a room-ventilating air register, a stationary disk having a central shaft-receiving opening and air-conducting openings around said central opening, a rotatable disk disposed at one side of said stationary disk and having air-conducting openings for registration with those aforesaid, a central shaft having a driving connection with said rotatable disk, said shaft being rotatably mounted in said shaft-receiving opening of said stationary disk, and an air deflector mounted on, carried solely by and rotatable bodily with the room-facing end of said shaft, said deflector being of substantially conical form and diverging toward its periphery from said disks, said deflector being exposed at the room side of the register, allowing its periphery to be gripped to rotate the shaft and rotary disk.

In testimony whereof I have hereunto affixed my signature.

ROBERT HUDSON WAGER.
